UNITED STATES PATENT OFFICE.

NANCY E. PETTITT, OF JUNCTION, TEXAS.

ENVELOP-SEAL.

1,023,034.

Specification of Letters Patent.

Patented Apr. 9, 1912.

Application filed April 25, 1910. Serial No. 557,494.

To all whom it may concern:

Be it known that I, NANCY E. PETTITT, a citizen of the United States, residing at Junction, in the county of Kimble, State of Texas, have invented certain new and useful Improvements in Envelop-Seals; and I do hereby declare the following to be a full, clear, and exact description of the invention, such as will enable others skilled in the art to which it appertains to make and use the same.

This invention relates to sealing devices for envelopes, newspaper wrappers and the like, more particularly relating to devices of this character in which oppositely turned convex disks are employed to clamp together the meeting edges of the wrapper so that the wrapper must be mutilated beyond repair before access to its contents may be obtained.

The object of this invention is to provide a sealing device which may be securely fastened in position with less labor than hitherto, and which will present a smooth surface to the contents of the wrapper so that the same is preserved from injury during transit to its destination.

The invention resides in the combination of parts hereinafter more fully described and claimed.

In the accompanying drawing forming part of this specification, Figure 1 is a perspective view of an envelop equipped with a seal constructed in accordance with my invention. Fig. 2 is an enlarged longitudinal sectional view of my improved seal showing the parts assembled for sealing. Fig. 3 is a longitudinal sectional view through the seal showing the parts sealed. Fig. 4 is a detail perspective view of one of the shells. Fig. 5 is a detail perspective view of the locking disk. Fig. 6 is a detail perspective view of the mating or guard shell.

Referring to the parts by their reference characters, 5 designates an envelop having a closing flap 6. The seal comprising the subject matter of this invention consists of an upper convex disk 7 having peripheral fastening prongs 8 which are engaged through the envelop flap and clenched on the under side thereof as will presently be described. Projecting axially through the shell 7 is a locking stud 9 which is of sufficient length to project through the flap 6

and body of the wrapper 5 and terminates in a retaining knob 10.

A convex shell 11 is arranged upon the inner face of the body of the envelop and is provided with marginal fastening prongs 12 which are sufficient in length to project through the body of the envelop and be clenched on the outer side thereof as shown in Fig. 2.

Arranged within the shell 11 is a substantially flat disk 13 which will be herein-after referred to as a locking disk, and which is peripherally secured to the concave face of the convex shell 11 by a line of solder or similar cement. The locking disk is provided with a centrally located opening 15 of sufficient cross dimension to receive the locking stud 9, the head of which latter projects a slight distance beyond the bottom face of the locking disk. Arranged upon the bottom face of the locking disk is a pair of 75 oppositely disposed resilient lips 16 the free ends of which engage the locking stud in the rear of its retaining head, the latter engaging the lips when the operation of mounting the seal has been completed and 80 positively preventing the withdrawal of the locking stud.

In applying the seal, the concave shell 11 containing the locking disk 13 is placed with its prongs engaging the inner face of the envelop body. The prongs are pressed through the envelop body and clenched on the outer side thereof. The shell 7 which is of less diameter than the locking disk 13 is now placed in engagement with the outer 90 face of the envelop flap and firmly pressed thereagainst, this operation causing the prongs 8 to pierce through the flap when they may be readily clenched upon the inner face thereof. The envelop flap is now 95 closed and pressed firmly against the envelop body until the locking stud 9 pierces through the envelop body and engages the resilient lips 15. When the seal has been thus applied, it will be noted that the disk 11 acts as a guard to prevent the resilient lips and locking stud from impinging against the contents of the envelop and mutilating the same.

From the foregoing description taken in 105 connection with the accompanying drawing, it is thought that the construction and operation of my invention will be easily under-

stood without a more extended explanation, it being understood that various changes may be made in the minor details of construction within the scope of the appended 5 claim.

What is claimed is:—

The combination in an envelop seal, of a pair of shells, a stud attached to one of said shells, a head formed upon said stud 10 and connected thereto by a tapered neck, a disk secured to the other of said shells and provided with an opening for receiving said head, a pair of leaf springs secured to said

disk and having their free ends in contact with each other, grooves formed in the terminals of said leaf springs and producing a circular aperture, said springs adapted to contact with the tapered neck of the head, and hold the shells rigidly with respect to each other. 15

In testimony whereof, I affix my signature, in presence of two witnesses.
